UNITED STATES PATENT OFFICE.

CHARLES W. DAKE, OF CHICAGO, ILLINOIS.

ADJUSTABLE HUB-PLATE.

1,393,884.

Specification of Letters Patent.

Patented Oct. 18, 1921.

Application filed July 21, 1919. Serial No. 312,265.

To all whom it may concern:

Be it known that I, CHARLES W. DAKE, a citizen of the United States, residing at Chicago, in the county of Cook and State of Illinois, have invented a certain new and useful Improvement in Adjustable Hub-Plates, of which the following is a specification.

My invention relates to means for taking up or adjusting for wear on the wearing plate associated with a wheel hub, particularly in the case of a locomotive. The invention is illustrated in the accompanying drawings wherein—

15 Figure 1 is a cross section on the line $\alpha-\alpha$ of Fig. 3 with my devices attached;

Fig. 2 is a detail cross section;

Fig. 2^A is a modified form of Fig 2;

20 Fig. 3 is a plan view of the cam surface of the wearing plate;

Fig. 4 is a plan view of the cam surface of the ring;

Fig. 5 is a cross section on the line $\alpha-\alpha$ of Fig. 4.

25 Like parts are indicated by the same letters in all the figures.

A is the hub, B the wearing plate, C the ring, the cam surface of the ring consisting of a series of concentric annuli DD, each 30 having a surface which consists of a series of cam surfaces D¹D¹. These surfaces on each annulus are staggered with reference to those on the next annulus.

Corresponding annuli EE are found on 35 the inner or cam surface of the plate and they also are broken up into a series of cam surfaces E¹E¹ corresponding to the similar surfaces on the ring.

Associated with the ring and the hub, are 40 a series of dowel-pins FF to prevent the ring from rotating on the plate.

The outer edge of the plate is provided with a series of notches GG with which are associated pins G¹G¹, having ends G² which 45 are received into the notches. The pins G¹ are screw threaded at G³ into the hub and have reduced surfaces G⁴ associated with a transverse screw threaded pin G⁵ which serve to lock the pins G¹ in position and thus 50 to lock the plate B in position when it has been advanced to the proper position, as for example as illustrated in Fig. 2.

J is an inwardly projecting flange on the back of the wearing plate and J¹ is an under 55 lying lip on the ring, whereby the plate B

is prevented from disengaging itself from the ring C.

It will be understood, of course, that these various parts may be greatly changed in size, proportion and arrangement without departing from the spirit of my invention. 60 What I have shown is therefore to be taken as diagrammatic, although it does not in the substance set forth a working structure.

The use and operation of my invention 65 are as follows:—

Assuming the parts to be constructed as indicated and related as shown in Fig. 1, if the plate B should have been worn so as to require adjustment, the pins G¹ are re- 70 tracted so as to disengage from the notches G and the plate is turned in the proper direction on the ring so that the several engaging cam surfaces travel on each other until the plate B has been sufficiently advanced, 75 laterally to accommodate for the wear. The pins G¹ are then screwed forward so as to bring their ends into the notches and the lock screws G⁵ are advanced so as to lock the pins G¹ in position and thus prevent further rotation of the plate B. During all 80 these actions, the ring C is prevented from rotation by the dowel pin F and the plate B is held in proper contacting relation with the ring C by the coacting flange and lip J 85 and J¹. The plate B may be rotated by any desired means.

By this arrangement of concentric annuli, each consisting of a series of inclined surfaces and these surfaces being staggered 90 with reference to those of the next annulus, a relatively uniform support is furnished for the wearing plate, so as to prevent it from giving or buckling or bending under the strains to which it is subjected. 95

I have shown five annuli each with two inclined surfaces. There might be any number of annuli greater than one and any number of inclined surfaces on each, from one up. It is only necessary to stagger these 100 surfaces or arrange them so that the end of any one surface is staggered with reference to the adjacent surface on the next annulus to get the desired result. As the action is the same whether there be one or any larger 105 number of inclined surfaces on each annulus, I wish the term "series of surfaces" as applied to the face of the annulus, to be understood as meaning one or more inclinations.

I have spoken of the hub as having an annular recess but it may easily be understood that the same effect would be obtained by having a flange, plate or ring properly disposed and it will also be understood that the recess could be in the plate and the other projecting parts on the hub. It will also be understood that the recess, as to some features of the invention, might be dispensed with entirely and in such case, the word "recess" as I use it in the claims, should be understood to refer only to the contacting parts or opposed parts of the plate and hub, although the recess, whether placed on the plate or away, is so minute as to be negligible or entirely dispensable.

I have spoken of this device as an adjustable hub plate but, of course, it is perfectly obvious that the word "hub" may here be taken in a broad sense to include any or all parts against which the plate bears and while I have contemplated the application of my invention to the hub of locomotive wheels, it might be used with any other device where such an adjustable plate is desired. The word "hub" therefore, is to be understood as anything which in effect would be the bearing part against which the plate abuts.

30 I claim:

1. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring.

2. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring, and means for locking the plate and ring together, so that while they may rotate one with reference to the other, they are retained in contact with each other.

3. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring, and means for locking the ring in position while the plate is being turned.

4. A hub having an annular recess on one

side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring and means for locking the plate against rotation in relation to the rim.

5. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring and means for locking the plate and ring together so that while they may rotate one with reference to the other, they are retained against axial separation from each other, and means for locking the ring in position while the plate is being turned.

6. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring and means for locking the plate and ring together so that while they may rotate one with reference to the other, they are retained in contact with each other, and means for locking the plate in any predetermined position.

7. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring, and means for locking the ring in position while the plate is being turned, and means for locking the plate in any predetermined position.

8. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring and a cooperating lip and flange, one on the ring and the other on the plate to prevent them from separating while

one of them rotates with reference to the other.

9. A hub having an annular recess on one side, in combination with a ring seated in the recess and having an outer surface which consists of a series of concentric annuli each composed of inclined surfaces staggered with reference to those of the adjacent annulus, and a wearing plate having a projection which extends into the recess and is provided with a surface corresponding to that of the ring, said plate having a series of notches and a series of pins adapted to enter the notches to lock the plate in its predetermined position.

10. A hub having an annular recess on one side in combination with a ring seated in the recess, having an outer surface which consists of a series of concentric annuli each having an inclined surface staggered with reference to that of the adjacent annulus and a wearing plate having a projection which extends into the recess and is provided with a surface corresponding to that of the ring, 20 and a corresponding lip and flange, one on the ring and the other on the plate to prevent them from separating while one of them rotates with reference to the other.

11. A hub having an annular recess on one side in combination with a ring seated in the recess, having an outer surface which consists of a series of concentric annuli each having an inclined surface staggered with reference to that of the adjacent annulus and a wearing plate having a projection which extends into the recess and is provided with a surface corresponding to that of the ring, 35 and a corresponding lip and flange, one on the ring and the other on the plate, to prevent them from separating while one of them rotates with reference to the other, their adjacent faces inclined in the same manner as the other contacting surfaces of ring and plate.

45 12. A hub having a bearing surface in

combination with a ring seated on such surface and having an outer surface which consists of a series of concentric annuli, each having an inclined surface staggered with reference to that of the adjacent annulus, 50 the wearing plate having a projection which bears against the surfaces of these annuli and is provided with a surface corresponding to that of the ring.

13. A hub having an annular recess on one side, in combination with a ring seated in the recess and having an outer surface which consists of a series of concentric annuli each composed of inclined surfaces staggered with relation to those of the annulus, and a wearing plate having a projection which extends into the recess and is provided with a surface corresponding to that of the ring and means for locking the plate and ring in position during the rotation of the plate, and separate 60 means for locking the plate in any predetermined position.

14. A hub having an annular recess on one side, in combination with a ring seated in the recess and having an outer surface 70 which consists of a series of concentric annuli each composed of inclined surfaces staggered with relation to those of the annulus, and a wearing plate having a projection which extends into the recess and is provided 75 with a surface corresponding to that of the ring and means for locking the plate and ring in position during the rotation of the plate, and separate means for locking the plate in any predetermined position, said 80 means being separate from and out of contact with the ring and the ring locking means.

In testimony whereof, I affix my signature in the presence of two witnesses this 16th day 85 of July, 1919.

CHARLES W. DAKE.
